UNITED STATES PATENT OFFICE.

MUSTAFA E. HAKKY, OF PROVIDENCE, RHODE ISLAND.

DESIGN FOR A SEWING SET.

Application filed January 23, 1928. Serial No. 25,000. Term of patent 7 years.

To all whom it may concern:

Be it known that I, MUSTAFA E. HAKKY, a citizen of the Republic of Turkey or the present government of that country, residing at Providence, in the county of Providence and State of Rhode Island, have invented a new, original, and ornamental Design for Sewing Sets, of which the following is a specification, reference being had to the accompanying drawing, forming part thereof.

I claim:

The ornamental design for a sewing set, substantially as shown.

In testimony whereof I have affixed my signature.

MUSTAFA E. HAKKY.
